UNITED STATES PATENT OFFICE.

EDGAR KIDWELL, OF MILWAUKEE, WISCONSIN, ASSIGNOR TO KIDWELL BOILER COMPANY, OF MILWAUKEE, WISCONSIN, A CORPORATION OF WISCONSIN.

STEAM BOILER.

Application filed December 4, 1923. Serial No. 678,408.

This invention relates to steam boilers of the series tube and drum type, having especial reference to a modification of or improvement in the supplemental water circulation path of the boiler forming the subject of Letters Patent of the United States No. 1,442,433 dated January 16, 1923, which supplemental path and the main water circulation path of the boiler are so co-ordinated that the true level of the boiler water is maintained within the steam-discharge drum.

According to my present invention one of the tube connections of the supplemental path is inclined to effect an upward current or flow of water from one steam-and-water drum to the other steam-and-water drum, and the other tube connection of said path is horizontally disposed and so arranged as to permit the water which flows through the inclined tube to return to the drum from which it originated, and to effect and maintain a substantially equal level of the water in the two drums, as will be hereinafter described and claimed.

The annexed drawing illustrates a longitudinal vertical section of a water-tube boiler embodying my invention. In this boiler the main water circulating path comprises an upper rear steam-and-water drum 5; a lower mud drum 6, and a forward water drum 7 on a plane between the drums 5, 6, all said drums being connected in succeeding order by banks of tubes 8, 9 and 10.

The steam space of the drum 5 is connected by means of overcomer or superheater tubes 11 with the steam space of an upper forward steam-and-water drum 12, whereby the steam which is disengaged from the water in the drum 5 passes over to the steam space of the drum 12, whence it is withdrawn for service. The water spaces of the drums 5 and 12 are connected by means of horizontal and inclined tubes 13, 14, respectively, which are located in the heating zone of the furnace, which tubes, together with the drum 12, provide a supplemental circulation path into and through which a relatively small portion of the water is diverted from the main path of circulation in such a manner as to maintain in the drum 12 a volume of water at substantially the same level as the water in the drum 5.

In the present instance the horizontal tube or tubes 13 are arranged in a plane below

the level of the water in the drum 5 so as to permit the free flow of the water from the disengaging drum to the drum 12, and the inclined tube or tubes 14 are arranged to effect a forced rearward and upward flow of the water from the drum 12 to the disengaging drum 5; the cross-sectional area of the horizontal tube or tubes 13 being such as to equalize the influx and efflux of water into and from the drum 5 with a difference of water level or head in drum 5 above that in drum 12 so small as to be negligible, thus maintaining a practically uniform voluminal flow of water through the supplemental path and insuring a substantially equal level of the water in the two drums. In other words, steam formed in the horizontal tubes 13 does not serve to create a current or flow in any definite direction, whereas the steam generated in the inclined tubes 14 causes a forced flow to the drum 5. Hence unless the cross-sectional area of the tubes 13 be such in relation to that of the tubes 14 as to accommodate the forced influx of water into the drum 5, the water in the latter will stand higher than that in the drum 12 to an extent necessary to give the head required to force the water through the tubes 13 to the drum 12, and consequently the water in the drums will not be maintained at substantially the same level.

While in the form of my invention herein illustrated the tube connection 14 is inclined to cause a water flow from the forward to the rearward steam-and-water drum, yet it is to be understood that, in pursuance of the principle of the invention, the inclination of such connection may be reversed to effect a flow from the rearward to the forward drum.

I claim—

1. A steam boiler having a continuous main water circulation path and a supplemental water circulation path, said main path including a steam-and-water receptacle wherein the steam is disengaged from the water, and said supplemental path comprising a steam-and-water receptacle from which the steam is discharged, said latter receptacle being outside the main path of circulation, and said supplemental path also comprising two tube connections between the water spaces of the two receptacles, one of said connections being inclined upwardly in its path from one receptacle to the other, and the other connection being horizontally dis-

posed between the two steam and water receptacles and being of such cross-sectional area as to permit the flow from said other to said one receptacle of a volume of water substantially equal to that of the forced flow of water through the inclined connection.

2. A steam boiler having a rear transverse steam-and-water drum, a front water drum, a rear mud drum, banks of tubes successively connecting the said drums, a front steam-and-water drum, supplemental circulation tube connections between the water spaces of the steam-and-water drums, one of said connections being horizontally disposed from one steam and water drum to the other and the other of said connections being inclined upwardly from one drum to the other and being of such cross-sectional area as to permit the flow from said other to said one drum of a volume of water substantially equal to that of the forced flow of water through the inclined connection.

3. A steam boiler having a rear transverse

steam-and-water drum, a rear mud drum, banks of tubes successively connecting the 25 said drums, a front steam-and-water drum, supplemental circulation tube connections between the water spaces of the steam-and-water drums, one of said connections being horizontally disposed from one steam and 30 water drum to the other and the other of said connections being inclined upwardly from the front steam-and-water drum to the rear steam-and-water drum, the cross-sectional area of the horizontal connection being such as to permit the flow from the rear to the front steam-and-water drum of a 35 volume of water substantially equal to that of the forced flow of water through the inclined connection from the front to the rear 40 steam-and-water drum.

Signed at Milwaukee, in the county of Milwaukee and State of Wisconsin, this 30th day of November A. D. 1923.

EDGAR KIDWELL.
